CLAIM

The ornamental design for a car interior, as shown and described.

DESCRIPTION

FIG. 1 is a forward perspective dashboard cut-away view of a car interior;

FIG. 2 is a left perspective cut-away view thereof;

FIG. 3 is a top, left perspective cut-away view thereof; and, FIG. 4 is a left, front perspective cut-away view thereof.

The broken lines form no part of the design.

The exterior car body portions shown in the cut-away views form no part of the design.
